UNITED STATES PATENT OFFICE.

GEORGE DIETZ, OF NEW YORK, N. Y.

SAFETY DOOR LOCK.

Application filed October 19, 1923, Serial No. 669,471.

To all whom it may concern:

Be it known that I, GEORGE DIETZ, a citizen of Germany, residing at New York, in the county of New York and State of New York, have invented certain new and useful Improvements in Safety Door Locks, of which the following is a specification.

The main object of this invention is to provide a device by means of which a door may be securely locked in closed position without the aid of a key or the usual locking means.

Another object is to provide a door lock which is placed between the door and the sash and is manipulated in such manner that the device is fixed to the sash, and a flange on the device engages the door to prevent the latter from being opened while the device is in such position.

These and other objects will become apparent in the description below, in which characters of reference refer to like-named parts of the drawing.

Referring briefly to the drawing, Figure 1 indicates a front elevational view of the device somewhat enlarged.

Figure 2 is a cross-sectional view taken on line 2—2 of Figure 1, showing the locking jaws in released position.

Figure 3 is a cross-sectional view taken on line 3—3 of Figure 2 and shows the locking jaws slightly extended and in engageable position.

Figure 4 is a cross-sectional view thru a door, showing the method of locking the door in closed position with this device.

Figure 5 is a cross-sectional view taken on line 5—5 of Figure 1.

Figure 6 is a perspective view of one of the locking jaws.

Figure 7 is an elevational view of the upper portion of a door and door frame, showing the locking device in position thereon.

Referring in detail to the drawing, the numeral 10 indicates the vertical frame posts in which a door 11 is pivotally mounted on hinges 12. This door is of the usual construction capable of a 90 degree swing and the posts 10 are provided with moulding strips 13 upon which the door shoulders when in closed position. The ordinary door construction usually has a space 14 between the upper edge of the door and the upper frame 15, and a similar space 16 between the frame post 10 and the outer edge of the

door. The device being mentioned in this description is adapted to be inserted into these spaces for locking the door in closed position. The locking device essentially consists of a pair of side frame bars 17 connected at their upper ends by a similar bar 18, and a bar 19 connects the lower ends of the side bars 17, these bars forming a rectangle. The side bars 17 are provided with projecting pins 20 which pass thru the bars 18 and 19 and are peened-over to secure the last-named bars rigidly to members 17. The lower bar 19 is provided with a curved surface 21 which has its high point at the rear edge and extends curvilinearly downwardly to the front face of the bar 19. The side bars are provided with vertical V-grooves 22 in which the ends 23 of a carriage 24 are slidably mounted. This carriage has an ear 23^a intermediate its length and from which a threaded shaft 24^a extends downwardly thru an opening in the lower bar 19 and projects somewhat from said bar. A wing nut 25 engages the threaded end 24^a of the shaft, and the shank 26 of the wing nut has a recessed annular channel 27 formed thereon in which the ends of stay brackets 28 are engaged, said brackets being rigidly secured to the bar 19. A pair of swing jaws 29 and 30 are used with the device and are provided with a pair of teeth 31 which project from their lower edge and are curved so as to ride upon the curved surface 21. These jaws are provided with mutually adjacent corners and a cut-out portion, from the upper ends of which pins 32 project, said pins being rotatably engaged in openings in the sides of the ear 23^a. A band envelopes the frame in a horizontal plane near the upper ends of the side bars 17, and comprises a relatively narrow portion 33, the sides of the band being of the same width, and the rear portion 34 being of a substantially greater width. The purpose for this band will be more fully hereinafter described. In order to retain the door within the frame in closed position, a flange 35 projects from the side of the lower bar 19 and is adapted to be engageable with the side surface of the door 11.

In use, the device is inserted in either of the spaces 14 or 16, and at any position, it being obvious that the upper horizontal bar 18 enters the space first, and in such position that the flange 35 lies in contact with the surface of the door 11, as illustrated in

Figures 4 and 7. When the device is inserted in either of said spaces, the locking jaws 29 and 30 are aligned with the surface of the side bars 17 and in the position as indicated in Figures 1, 2, and 3. By rotating the wing nut 25 in the proper direction, the shaft 24 will urge the carriage 24 downwardly in the V-grooves 22, thus causing the teeth 31 of the jaws 29 and 30 to ride outwardly from one side of the frame upon the curved surface 21 of the lower frame member 19. The projecting curved ends of the teeth will consequently engage the material forming the door frame 10 or 15. Continued rotation of the wing nut will urge the carriage 24 to travel further downwardly, thus causing the jaws 29 and 30 to be rotated thru a greater degree of arc about the pins 32, the rear portion 34 of the band serving as a support for the carriage when the jaws are in completely or partially extended position. When in extended position, the jaws will substantially assume the position as shown in Figure 4. From this illustration, it will be seen that the person on the outside of the door pushing the same will be prevented from opening said door, as the extending jaws 30 will be engaged in the door frame while the flange 35 will engage the door, thus preventing the latter from being opened. In order to release the device from the locked position, the wing nut 25 is rotated in an opposite direction and causes the shaft to lift the carriage 24, thereby drawing the jaws out of the door jamb, the front band 33 folding the jaws into the position shown in Figure 2 during this drawing operation, the wing nut being at all times held stationary position by the brackets 28.

I claim:—

1. A device of the class described comprising a rectangular frame, the sides of said frame having grooves therein, a carriage extending across said frame and engaged in said grooves, a threaded shaft rigid with said carriage, a wing nut engaging said shaft, said wing nut when rotated being adapted to lift or lower the carriage, the frame being insertable between a door and door frame, and means on said carriage for engaging said door frame.

2. A device of the class described comprising a rectangular frame, the sides of

said frame having grooves facing each other, a carriage slideable between the sides of said frame, a threaded shaft rigid with the carriage, a thumb nut engaging said shaft, jaws pivotally mounted on said carriage, said frame being insertable between the door and door frame, means for extending the jaws into the door frame, and means for preventing the opening of said door when the jaws are extended.

3. A device of the class described comprising a rectangular frame, the sides of said frame having grooves facing each other, a carriage slideable between the sides of said frame, a threaded shaft rigid with the carriage, a thumb nut engaging said shaft, jaws pivotally mounted on said carriage, said frame being insertable between the door and door frame, curved teeth on the lower end of said jaws, a curved surface on the rectangular frame supporting the teeth of said jaws, said wing nut when rotated being adapted to lower the carriage in the slides and cause the teeth to rotate downwardly on the curved surface of the frame, and means on said frame for retaining a door in closed position when the jaws are extended.

4. A device of the class described comprising a rectangular frame, the sides of said frame having grooves facing each other, a carriage slideable between the sides of said frame, a threaded shaft rigid with the carriage, a thumb nut engaging said shaft, jaws pivotally mounted on said carriage, said frame being insertable between the door and door frame, curved teeth on the lower end of said jaws, a curved surface on the rectangular frame supporting the teeth of said jaws, said wing nut when rotated being adapted to lower the carriage in the slides and cause the teeth to rotate downwardly on the curved surface of the frame, a flange extending from the lower portion of the rectangular frame and adapted to engage the side of the door, a band enveloping the frame forming a support for the carriage when the jaws are in extended position, the front portion of the band providing means for folding the jaws into the frame when said jaws are extracted from the door frame.

In testimony whereof I affix my signature.

GEORGE DIETZ.
